United States Patent Office

Des. 196,018
Patented Aug. 13, 1963

196,018

PORTABLE STOVE

Landon L. Palmer and Stephen Morgenstern, Toledo,
Ohio; said Morgenstern assignor to said Palmer

Filed Oct. 1, 1962, Ser. No. 71,929

Term of patent 14 years

(Cl. D81—10)

Fig. 2

Fig. 3

Fig. 1

FIG. 1 is a top perspective view of a portable stove showing our new design;

FIG. 2 is a side elevational view thereof, shown partly in section; and

FIG. 3 is a top perspective view of the base portion thereof.

The side not shown is substantially like the side shown.
We claim:

The ornamental design for a portable stove, as shown and described.
